J. SYLVAN

WINDOW CONSTRUCTION

Filed June 21, 1922

UNITED STATES PATENT OFFICE.

JOSEPH SYLVAN, OF CICERO, ILLINOIS.

WINDOW CONSTRUCTION.

Application filed June 21, 1922. Serial No. 569,806.

To all whom it may concern:

Be it known that I, JOSEPH SYLVAN, a citizen of the United States, and a resident of Cicero, in the county of Cook and State of Illinois, have invented certain new and useful Improvements in Window Construction; and I do hereby declare that the following is a full, clear, and exact description thereof, reference being had to the accompanying drawings, and to the letters of reference marked thereon, which form a part of this specification.

This invention relates to improvements in window construction and consists of the matters hereinafter described and more particularly pointed out in the appended claims.

The primary object of the invention is to provide in a double hung window, a simple and efficient means for locking the lower sash against movement after it has been swung inwardly into the room, for the purpose of providing ventilation or for cleaning the outside thereof.

Another object of the invention is to provide a novel means for preventing the sash from swinging into the room under wind pressure.

A further object of the invention is to provide an improved groove strip to which the slide strips of the sash are connected for a sliding engagement, which strips effectively prevent rattling of the sash and the entrance of dust and wind at the sides of the sash.

These objects of the invention as well as the several advantages thereof will more fully appear as I proceed with my specification.

In the drawings:—

Fig. 1 is a vertical sectional view through a window construction embodying my invention.

Fig. 2 is an enlarged view of the parts shown in the bottom end of Fig. 1 with several of said parts in a changed relation.

Fig. 3 is a horizontal sectional view as taken on the line 3—3 of Fig. 1.

Fig. 4 is a view in front elevation of the parts shown in the Fig. 2.

Fig. 5 is a perspective view of a novel stop or locking plate embodied in my improved window construction.

Fig. 6 is a cross section through one of the groove strips embodied in my improved window construction.

Referring now in detail to that embodiment

of the invention illustrated in the accompanying drawings:—10 indicates as a whole, a window frame and 11 and 12 indicate the bottom and top sash associated therewith. The window frame comprises 60 the upright side members 13, a top or lintel 14 and a sill 15, all of the usual construction.

Each side member includes inner and outer moulding strips 16 and 17 respectively, 65 and an intermediate parting strip 18, said strips defining in each side member, the inner and outer channels or grooves 19 and 20 for the bottom and top sash (see Fig. 3).

In the outer groove 20 of each side member of the frame 10 and extending from lintel to sill thereof is a combined guide and weather strip 21, hereinafter termed "a groove strip", (see Figs. 3 and 6). Said strip is made of sheet metal, bent into a channel form and includes a main web 22 and inner and outer side flanges 23 and 24, respectively, arranged at substantially a right angle to the plane of the main web. Said flanges 23 and 24 terminate in inner and outer hook flanges 25 and 26, extending parallel with the web 22 and both facing in the same direction, the hook flange 26 being offset into a plane spaced from that of the hook flange 25.

The groove strips 21 are held in place by screws 27 (see Fig. 3) which pass through the main web into the side members of the frames, the heads of the screws being spaced from the web to permit a limited lateral shifting of the strip when necessary. When the groove strips are in place in their respective outer grooves of both side frame members, the hook flanges 25 are arranged in the plane of but are spaced from the parting strips 18 while the hook flanges 26 are arranged in the plane of but are spaced from the outer moulding strips 17.

Associated with each hook flange 25, 26, are slide strips 28 and 29 respectively, there being a pair of such slides for each sash. Each slide strip is of a length substantially equal to that of the associated sash and is made of sheet metal bent into suitable cross-sectional shape. The outer marginal part of each slide strip 28 and 29, is provided with a hook flange 30 and 31 respectively, having engagement with the hook flanges 25 and 26 of the groove strip, so that said slide strips are guided for a vertical movement.

with reference to the groove strip. The inner marginal part of each slide strip is folded over upon itself as indicated at 32 and 33 respectively, to stiffen the strips along this margin.

Fixed to the side edges of each upright member of each sash is a strip 34, the inner marginal part of which is bent over to provide a hook flange 35 adapted to embrace the folded over marginal parts 32 and 33 of the slide strips. The slide strips 28 and 29 of the bottom and top sash are pivotally connected to their respective sash near their bottom ends as indicated at 36 in Figs. 1 and 2. Each sash is connected by sash cords 37 to the usual weights (not shown) in the side members of the frame, the cords being attached to the sash by the same pins which provide the pivotal connection 36 before mentioned.

In the inner grooves 19 of each side member of the frame, is located a spring strip 39, which extends from lintel to sill. Each spring strip is fixed along one margin to the associated side frame member near the parting strip, while the other margin 40 of each strip is bent over into a plane to engage the hook flange 35 of the associated sash strip and acts to center the sash in the frame and to provide a weatherproof joint at the sides of the bottom sash (see Fig. 3).

Means are provided for holding the bottom sash 11 in any one of its inward swung, open positions. Said means include a plate 41, which is fixed to the face of each of the inner moulding strips 16 near the sill 15. Each plate has an elongated, horizontally extending slot 42 which is curved downwardly as at 43 at one end, to provide an entrance opening or mouth in that edge of the plate adjacent the sash. That part 44 of the plate above the slot 42 terminates short of the part 45 below the slot 42 and in said part 45 near the mouth 43 of the slot are two notches 46 and 47 respectively, which open upwardly into said slot.

On the bottom end of each side member of the bottom sash is secured a plate 48, including a laterally extending stud 49, which when the bottom sash is in its closed position, as shown in full lines in Fig. 1, engages upon that curved surface of the lower part 45 of the plate 41, defining a part of the mouth 43 of the slot. When the top end of the sash 11 is swung inwardly about the pivots 36 as an axis, the studs 49 will ride upwardly on those parts of the plates upon which they engage to enter the mouths 43 of the slots 42 and then pass into the first notches 46 of said plates. This will hold the sash in the dotted line position 11^a in Fig. 1 against any further inward swinging movement under wind pressure or against an upward movement, should it be attempted to "raise" the sash while in this position.

Should more ventilation be desired, it is only necessary to lift the sash upwardly, just enough to clear notches 46 and then swing the sash inwardly, until the studs 49 enter the second notches 47, when the sash is held in the second dotted line position 11^b, as shown in Fig. 1. Should it be desired to clean the outer surface of the sash pane, the sash would be "raised" sufficiently and then swing inwardly until the studs 49 engage in the closed inner ends of the slots 42, when the sash will be in a substantially horizontal position, the outer surface of the pane then being readily accessible for cleaning from the inside of the room.

Should it be desired to "raise" the bottom sash, this is done in the usual manner, the pins or studs 49 readily passing the top parts 44 of the plates 41 by reason of the spacing back of the edges of said top parts 44 as before described.

To prevent the bottom sash from swinging inwardly under wind pressure when it is in a raised position, wherein its bottom edge is above the plates 41, I provide inwardly extending flange strips 50 between the inner moulding strips 16 and spring strips 39, at the top ends of the side frame members.

The bottom ends of the strips 50 are spaced from the plates 41, a distance slightly greater than the height of the bottom sash, so that they will in no manner interfere with the inward swinging of the sash when it is in position to co-operate with the plates 41, as before described. However, when the bottom sash is "raised" into a position above said plates 41, the strips 50 will act to engage the side margins of the sash and prevent inward swinging movement.

When it is desired to clean the pane of the top sash, from the inside of the room, the bottom sash is first swung into its full open position, as shown in Fig. 2, after which the top sash is lowered to almost its limit in the frame and then swung inwardly to lie substantially flat upon the bottom sash. As the top end of the top sash swings inwardly about the pivot studs 36, the bottom end swings outwardly into the plane of the outer moulding strips 17 to engage beneath lugs 51 secured to the hook flange 26 of the channel strips for that purpose.

To prevent the inward swinging movement of the top sash under wind pressure when in its uppermost position, I provide inwardly projecting strips 52 on the hook flanges 25 of the groove strips. The bottom ends of said strips 52 are so positioned that they in no manner interfere with the inward swinging movement of the top sash when said sash is in the predetermined position wherein it operates as before described.

It is apparent that in the swinging movement of either sash, the hook flanges of the sash strips will slide over the folded over

margins of slide strips, there never being a complete disengagement between said hook flanges and said slide strip margins.

Should either sash contract in width, 5 the spring strips 39 will yield or the groove strips 21 will shift laterally to accommodate such contraction so as to maintain weather-proof joints between the frame and sash at all times.

10 While in describing my invention, I have referred to certain details of mechanical construction and arrangement of parts, I do not wish to be limited thereto except as may be pointed out in the appended claims.

15 I claim as my invention:—

1. In combination with a window frame and a sash therein capable of both a vertical sliding and an inward swinging movement, a plate fixed to the side-member of 20 the frame near its bottom end, said plate having a slot which opens through that edge of the plate adjacent the sash and having a notch which opens into said slot from below, and a laterally extending stud on the sash 25 so positioned with reference to said plate that, in the vertical movement of said sash, said stud will freely pass said plate but in the inward swinging movement thereof, said stud will enter the plate slot to be 30 engaged either in said notch or in the closed end of the slot to hold the sash in different angularly inclined positions.

2. In a combination with a window frame having side members provided with grooves 35 therein, top and bottom sash associated therewith, a groove strip in one groove of each side member, each groove strip having two hook flanges arranged in a plane spaced from said groove, slide strips, one associated 40 with each sash and having a hooked engagement with the flanges of the groove strips to permit a vertical sliding movement of the slide strips relative to the groove strips, and sash strips secured to the sash, 45 said sash strips being pivotally connected to the guide strips and adapted to embrace a part of the slide strips, whereby the sash is capable of either an inward swinging movement or a vertical sliding movement.

50 3. In a combination with a window frame

having side members provided with grooves therein, top and bottom sash associated therewith, a groove strip in one groove of each side member, each groove strip having two hook flanges, arranged in a plane 55 spaced from said groove, slide strips, one associated with each sash and having a hooked engagement with the flanges of the groove strips to permit a vertical sliding movement of the slide strips relative to the 60 groove strips, sash strips secured to the sash and pivotally connected at their bottom ends to the slide strips and adapted to embrace a part of the slide strips whereby the sash is capable of either an inward 65 swinging or a vertical sliding movement, and means securing the groove strips in the associated grooves, said means permitting a lateral shifting of each groove strip outwardly and inwardly of its groove to accommodate for the expansion and contraction of the sash.

4. In combination with a window frame having side members each provided with inner and outer, upright grooves, bottom 70 and top sash associated with said grooves, a groove strip in each outer groove, each groove strip having two hook flanges arranged in a plane spaced from said grooves, 75 slide strips associated with each flange of the groove strips, the slide strips of one sash having a hooked engagement with one set of flanges of the groove strips and the slide strips of the other sash having a hooked engagement with the other set of flanges of 80 the groove strips to permit a vertical sliding movement of the slide strips with reference to the groove strips, sash strips secured to the side members of the sash and pivotally connected with the slide strips, at 85 their respective bottom ends, and a spring strip in each inner groove engaging a part of the sash strip of the bottom sash to center the sash in the frame and to form 90 weather strips between the bottom sash and its associated grooves.

In testimony that I claim the foregoing as my invention, I affix my signature this 12th day of June, A. D. 1922.

JOSEPH SYLVAN.
